UNITED STATES PATENT OFFICE.

ALEXANDER MICHEL LOCHWITZKY, OF AUSTIN, TEXAS.

SHOE.

Application filed February 28, 1920, Serial No. 361,965. Renewed May 8, 1923.

To all whom it may concern:

Be it known that I, ALEXANDER M. LOCHWITZKY, a citizen of the United States, and resident of Austin, in the county of Travis and State of Texas, have invented a certain new and useful Shoe, of which the following is a specification, the same being a full, clear, and exact description of the invention, such as will enable others skilled in the art 10 to which it appertains to make and use the same.

This invention relates to foot coverings—as boots and shoes—which I designate as a "Siberian winter shoe," adapted to be worn 15 by lumbermen and other persons, whose occupation requires them to perform their work out of doors in cold weather, and sometimes in snow and ice, especially in countries where it is very cold, as in Siberia 20 and northern Russia, as well as in Canada and in the northern parts of the United States.

It is well known that leather, besides being slippery on ice, conducts the heat from 25 the foot and admits the cold, thus making it impossible to discover when the toes are frozen, which, after having been from eight to ten hours in that state, have frequently to be amputated.

30 I have therefore provided a foot covering that may be worn in comfort in very cold weather, as well as where there is ice, snow, or slush, and which comprises among other features a practically waterproof laminated 35 boot principally made of fabric, the upper part of which is composed of laminated flexible material, quilted together by cross ranges of stitching to form superposed air chambers and having massed laminations of 40 fibrous material therebelow, and also a laminated and preferably quilted sole and heel—together with reinforcing devices and retaining means—whereby I obtain a foot covering which possesses the essential properties 45 of great strength, flexibility and imperviousness to water, which retains the heat and keeps the foot warm while allowing evaporation and escape of perspiration, thus providing ventilation, and which may be 50 worn in winter with perfect safety and entire comfort.

With the above objects and other new and useful objects and features in view, which will be described below, the invention consists in the novel construction, arrangement 55 and operation of parts hereinafter set forth.

In the drawings, illustrative of one embodiment of the invention, which accompany and form a part of this specification,

Figure 1 represents a side elevation of an 60 article constructed according to my invention;

Figure 2 is a perspective view of the sole and heel thereof;

Figure 3 is a view in detail showing the 65 quilting of the fibrous material;

Figure 4 is a perspective view partly broken away to show the construction of the parts;

Figure 5 is a section taken on the line 5—5, 70 Figure 4;

Figure 6 is a section on the line 6—6, Figure 1;

Figure 7 a sectional detail view showing the structure of the sole and heel; and 75

Figure 8 is a view in detail showing how the parts are stitched together.

Referring particularly to the drawings, the numeral 1 denotes the various sheets of fabric which in laminated form comprise the 80 principal elements of the structure of the foot covering. Any suitable fibrous material may be employed for this purpose whether new, or whether it has been already used for other purposes, as for example, old suitings 85 or army blankets, etc. or parts of them, such as are now given over to army reclamation divisions, whereby a light, cheap and porous material may be provided which will be of low cost and long lived, besides having 90 such adaptability to climatic changes as will afford adequate protection from cold.

The various layers or laminations may be quilted together by thread being sewed through the same in lines, as at 1", in such 95 a manner as to provide air chambers 10 within the cross ranges of stitches and between the laminations or in the cellular structure of the fabric, as by stretching one spaced set of layers 1 tightly and by laying the alternate layers 1' loosely over the same before performing the quilting operation, after which the parts may be sewed together. A greater or less number of laminations may be employed according to the requirements 100 of use to which the boot is to be subjected.

The material is preferably made up in massed sheets which may be cut out in lines to conform to the shape of the form of the foot and ankle when the cut out portions are 110 assembled. The lines of sewing or quilting of the stitched preferably upper portion of

- the shoe not only hold together the layers of fabric so as to prevent wearing one on the other, but keep them from stretching out of shape and they also serve to make channels in the fibrous material to facilitate the escape of perspiration. I preferably insert oil cloth or other waterproof material 2 between the layers of fabric to assist in preserving the waterproof properties of the shoe.
- 10 The laminations at the lower part of the leg are preferably massed together and the parts are also preferably strengthened or reinforced by vertically disposed braces 3 at points where there is the greatest wear,
- 15 which braces may enclose the meeting edges of the various pieces of the upper quilted laminations and the therebelow laminations of the fabric, and are preferably attached thereto by a plurality of seams 3' extending
- 20 from the toe to the top of the foot covering at the front and rear thereof, and which also aid in maintaining the integrity of the fabric and in preserving its desired contour and shape.
- 25 The toe and heel portion of the boot may be reinforced respectively by a vamp 4 and heel piece 5 preferably made of leather or analogous material which add to the appearance of the same and assist in preserving the shape thereof by increasing the substantiability of the covering.
- I also preferably use an adjustable strap 6 to conform to the shape of the shoe and ankle of the wearer and to assist in preventing the same from becoming loose at the instep and also in holding the shoe from slipping and preventing the same from bulging, and also for retaining it on the wearer. On account of the stretching or expanding nature of fibrous material, the strain of the instep upon the boot in use would be liable to stretch or expand the fabric so as to render the same loose and floppy, thus causing the foot to work or slip in the boot which
- 35 would present an unsightly appearance and cause discomfort. I obviate these objections and preserve the appearance of the material by the use of the said strap.
- I preferably form the composite sole of the shoe by laminations or layers of fabric 7 the edges of which are turned over at 7' and

sewed to a preferably leather sole 8 preferably having an interposed layer of oil-cloth or other waterproof material 2'. I may also use an insole comprising a layer 55 of leather 9 and one of fabric 9' superposed theron, the parts holding the insole in position, namely 7 and 8 being sewed together at 8'.

A supplemental sole 11 may comprise a series of laminations of fabric preferably quilted together, and also a heel 12 likewise comprising a series of laminations preferably quilted together, both sole and heel being sewed to the interposed leather sole 8 as 65 at 8''.

I wish it to be understood that I do not desire to be limited to the particular use or the exact details of construction shown and described, for obvious modifications will occur to persons skilled in the art.

What I claim as my invention is:—

1. A foot covering consisting of a laminated structure comprising layers of fabric, each alternate layer being tightly drawn 75 and the intermediate ones being loosely laid thereon so as to form when quilted together by cross ranges of stitches a series of adjacent air chambers.

2. A foot covering consisting of a laminated structure comprising layers of fabric, each alternate layer being tightly drawn and the intermediate ones being loosely laid thereon so as to form when quilted together a series of adjacent air chambers, and a series 85 of massed layers of fabric having edges, and also a strap to cover the meeting edges of the layers of quilted fabric and the layers of massed fabric to hold them from strain and to draw both of the same to the foot. 90

3. A foot covering comprising an upper laminated structure and a laminated sole therefor comprising layers of fabric turned in and attached to a piece of leather and having an interposed layer of waterproof material, and also having a supplemental sole and heel comprising layers of fibrous material quilted together fastened to the same. 95

Signed at New York city in the county of New York and State of New York, this 17th day of February A. D. 1920.

ALEXANDER MICHEL LOCHWITZKY.
